UNITED STATES PATENT OFFICE.

ALPHEUS M. GREER, OF RUNNELS COUNTY, NEAR GOLDSBORO, TEXAS.

DESIGN FOR A COMBINED KNIFE AND SAW.

46,091.

Specification for Design.

Patented July 14, 1914.

Application filed April 18, 1914. Serial No. 832,977. Term of patent 7 years.

To all whom it may concern:

Be it known that I, ALPHEUS M. GREER, a citizen of the United States, residing in Runnels county, State of Texas, near Goldsboro, Coleman county, State of Texas, have invented a new, original, and ornamental Design for a Combined Knife and Saw, of which the following is a specification, reference being had to the accompanying drawing, forming part thereof.

The figure is a perspective view of a combined saw and knife embodying my new design.

I claim:

The ornamental design for a combined knife and saw, as shown.

ALPHEUS M. GREER.

Witnesses:

J. F. STEVENSON,
J. W. BRIGHT.
